[57] CLAIM

The ornamental design for an automatic pipette or the like, as shown and described.

DESCRIPTION

FIG. 1 is a front perspective view of an automatic pipette or the like, showing my new design;

FIG. 2 is a front elevational view thereof;

FIG. 3 is a rear elevational view thereof;

FIG. 4 is a side elevational view thereof;

FIG. 5 is a top plan view thereof, and

FIG. 6 is a bottom plan view thereof.

The side opposite to the side shown in FIG. 4 is a mirror image thereof.
